UNITED STATES PATENT OFFICE.

WILLIAM C. LANG, OF CLEVELAND, OHIO.

TOY CANNON.

1,094,725.

Specification of Letters Patent.

Patented Apr. 28, 1914.

Application filed August 25, 1913. Serial No. 736,351.

To all whom it may concern:

Be it known that I, WILLIAM C. LANG, a citizen of the United States, residing at Cleveland, in the county of Cuyahoga and State of Ohio, have invented certain new and useful Improvements in Toy Cannons, of which the following is a specification.

My invention relates to improvements in toy cannons, the primary object being to provide a generally improved attractive appearing toy of this class of exceedingly simple, durable, and efficient construction, which may be readily loaded or discharged without any liability to breakage or disarrangement of the parts.

A further object is to improve the spring actuated plunger mechanism and to provide improved connecting breech mechanism, for moving said plunger mechanism to a loaded position, with improved trigger mechanism for automatically engaging the spring actuated plunger and for discharging or releasing the same when the toy is discharged.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Figure 1 is a side elevation of the improved toy cannon, the parts being shown in a normal position and the dotted lines indicating the position of the link and connected breech members when the spring actuated plunger is drawn to its loaded position. Fig. 2, a top plan view of the same, the lever link and connected breech members being shown in their retracted position in the act of loading. Fig. 3, a longitudinal sectional view of the cannon body. Fig. 4, a rear view of the improved toy cannon, the parts being in the position shown in Fig. 1. Fig. 5, a cross sectional view taken on line 5—5 of Fig. 3. Fig. 6, a fragmentary top plan view of the lower rear portion of the carriage and illustrating the cross or connecting member of the cheek-blocks for carrying the elevating screw and cannon balls.

Similar numerals of reference designate like parts throughout all the figures of the drawings.

55 The improved toy cannon comprises a

cannon body 1, of suitable form pivotally mounted on a carriage 2, by means of trunnions 1^a. The cannon body 1, is preferably made up of two longitudinally extending metallic shells connected at their ends by 60 means of lugs and rivets 1^b.

The side blocks or members of the carriage are preferably mounted upon and connected by means of connecting axle bars 3, provided with supporting wheels 4. The 65 side or cheek blocks 2, are also connected by means of a connecting member 5, the latter being threaded at its center to receive and contain the elevating screw 6, for supporting and adjusting the rear portion of 70 the cannon body in the usual manner, and said connecting bar or member 5, is also provided with ball receiving recesses or pockets 7^a, to receive and contain the cannon balls 7, the latter being preferably made 75 of rubber, or other suitable resilient material.

The cannon body is provided with a centrally located tubular member 8, extending longitudinally therethrough, said tubular 80 member or section forming the bore of the cannon body and being adapted to receive and contain the spring actuated plunger mechanism hereinafter described. The rear end of the tubular member or section 8, is 85 closed by means of a stationary breech block or member 9.

The spring actuated plunger mechanism comprises a movable breech member or knob 10, the latter being provided with a guide 90 link 11, slidably mounted in a pair of openings in the stationary breech member 9, said guide link 11, in the present instance, consisting of a single length of wire bent upon itself to form a loop member and said guide 95 link 11, is movably or flexibly connected to the plunger 12, by means of a second guide link 13, of similar form, said links 11 and 13, being surrounded by a coiled spring 14, mounted within the tube 8, and interposed 100 between the plunger 12, and the stationary breech member 9.

As a means for retracting the plunger 12, and compressing the spring 14, through the medium of the link members 11 and 13, and the movable breech or knob 10, a plurality of jointed link members are slidably and pivotally connected to the movable breech knob 10, said link members consisting, in the present instance, of a pair of lever links 110

15, pivotally mounted upon and carried by the side members of the carriage, the upper ends of said lever links being provided with guide slots 15^a, taking over and 5 adapted to slide upon a pivot pin 16, passing through the breech knob 10. The guide slots 15^a are adapted to slide upon and compensate for the relative movements of the parts as well as to allow for the adjustment 10 of the cannon body through the medium of the adjusting or elevating screw 6.

As a means for providing an operating handle or lever for coöoperating with the lever links 15, in the act of moving the plunger mechanism and its connections to a 15 loaded or retracted position as indicated in dotted lines in Fig. 1, and full lines in Fig. 2, a second pair of lever links 17, is provided said second pair of links being mounted 20 upon the pivot pin 16, and being provided with lugs or projections 17^a, adapted to come into contact with or engage with a pair of off-set or flanged members 15^b, at the upper end of the lever links 15, so that 25 when the lever links 17, are drawn rearwardly in the act of loading the toy cannon, the projection 17^a, will engage with the flanged or off-set portions 15^b, to form a jointed lever said links 17, being curved to 30 conform to and fit down over the rear portion of the cannon body preparatory to the loading operation above described, or just after such loaded operation and before discharging the toy, as illustrated in Figs. 1 35 and 4 of the drawings. The front portions of the lever links 17, are preferably bent to form a converged loop handle 18, adapted to normally rest upon the cannon body as shown.

40 As a means for automatically engaging the plunger 12, when compressed or retracted as hereinbefore described, a trigger member or lever 19, mounted within the cannon body above the tubular section 8, 45 said trigger member being mounted, in the present instance, between bearing lugs 20, the forward end of the trigger member being provided with a hooked head 19^a, operating between the guide flanges 21, struck 50 out from the tube 8, to form a top opening in the latter, said hooked head 19^a being beveled so as to ride upon the convolutions of the spring 14, as the latter is compressed in the loading operation, but when the plunger 12 passes under the head 19^a, the latter 55 will fall in front of the plunger and engage the same until the said hooked head is released by downward pressure upon the touch button 19^b, projecting upwardly at the rear 60 of the cannon body.

When the plunger 12, is retracted and engaged by the trigger member 19, the connection between the guide links or loop members 11 and 13, is such that these members 65 may telescope or pass into each other thus

permitting of the return or folding up of the lever links 15 and 17, in the position shown in Figs. 1 and 4 preparatory to discharging the toy cannon.

The tubular member 8, is provided at its 70 top with an opening communicating with an intersecting vertically disposed tube 22, the latter forming a ball receiving opening 23, through which the toy ball may be passed in the loading operation. 75

From the foregoing description, taken in connection with the accompanying drawings the operation and advantages of my invention will be readily understood.

Having thus described one of the embodiments of my invention, what I claim and desire to secure by Letters Patent is,

1. In a toy cannon, a carriage, a cannon body provided with a ball receiving opening, a spring resisted plunger therein, a breech member connected with the latter, jointed link members slidably and pivotally connected to said breech member, and a trigger member within said cannon body adapted to automatically engage said plunger 80 when drawn to set position at the rear of said ball receiving opening and to disengage the same. 85

2. In a toy cannon, the combination with a carriage and a cannon body provided with a spring resisted plunger; of a breech member, link members connecting the latter to said plunger, and pairs of jointed lever link members carried by said carriage and connected to said breech member, one pair 95 of lever link members being adapted to normally extend forwardly and to be folded over said cannon body in the loaded and unloaded positions of the parts. 100

3. In a toy cannon, a carriage, a cannon body, a tubular member extending therethrough, a spring resisted plunger member therein, a stationary breech member, a movable member provided with a link member 105 slidably mounted in said stationary breech member, a second link member connected to said plunger member and telescopically connected to said first mentioned link member, means for operating said movable breech member and a trigger member within the 110 top of said cannon body for automatically 115 engaging said plunger when the latter is retracted.

4. A toy cannon, comprising a carriage, a cannon body pivotally mounted thereon, and provided at its top with a vertically extending ball receiving tube, a tubular member extending therethrough intersected by said ball receiving tube and provided with a stationary breech member, a movable breech member provided with a guide link extending through said stationary breech member and into said tubular member, a second guide link movably connected to said first mentioned guide link and provided with a 120 125 130

plunger member in said tubular member, a coiled spring in said tube interposed between said plunger member and said stationary breech member, and a pivoted trigger member at the rear of said ball receiving tube and within said cannon body adapted to automatically engage said plunger member when moved to its initial spring or compressed position at the rear of said ball

receiving tube by said movable breech member.

In testimony whereof I have affixed my signature in presence of two witnesses.
